UNITED STATES PATENT OFFICE.

WILLIAM NEWBY, OF YOUNGSTOWN, OHIO.

METHOD OF OPENING SHEET AND TIN-PLATE PACKS.

Application filed May 23, 1921. Serial No. 471,840.

To all whom it may concern:

Be it known that I, WILLIAM NEWBY, a citizen of the United States, and a resident of Youngstown, county of Mahoning, and 5 State of Ohio, have invented a new and useful Improvement in Methods of Opening Sheet and Tin-Plate Packs, of which the following is a specification, the principle of the invention being herein explained and the 10 best mode in which I have contemplated applying that principle, so as to distinguish it from other inventions.

The present invention relates to a method 15 of opening sheet and tin plate packs by first crimping the packs and then flattening out the crimps. The object of the present invention is to more thoroughly open the pack by crimping it in an improved manner and thus separating the sheets more thoroughly 20 than has heretofore been done.

The annexed drawing and the following 25 description set forth in detail one approved method of carrying out the invention, such disclosed mode, however, constituting but one of the various ways in which the principle of the invention may be used.

In said annexed drawing:—

Fig. 1 is a perspective view of the crimping and flattening rolls showing the position 30 of the pack passing through the same; Fig. 2 is a diagrammatic section through the rolls to show the action of the crimping flutes as they travel across the pack; Fig. 3 is a diagrammatic view showing the crimps being formed and the resultant wave in the pack by the formation of the crisp.

In the usual methods employed in separating sheet and tin plate packs, the packs 40 are crimped at right angles to the edges or sides of the pack and then are passed through flattening rolls which are either parallel to the crimping rolls or at right angles to them. In the present method the pack is passed through two crimping rolls 2 which are provided with spiral flutes 3 and thus each corrugation 4 across the pack is formed gradually from one side toward the other instead of being rolled into the pack in the usual or old method. The corrugations or crimps 45 4 which are thus formed in the pack are at an acute angle A to the edge or side 5 of the pack rather than at a right angle as in the usual method. The crimped pack is then passed through a pair of flattening rolls 6 50 which are parallel to the crimping rolls and it will be seen from Fig. 1, that the flattening

rolls cover approximately four crimps at the same time and thus the crimped pack cannot weave through these flattening rolls and come out in a crimped condition. 60

By forming the crimps with rolls having spiral flutes as shown, the separation of the sheets is to a great extent, accomplished during the crimping operation. Where the crimps or corrugations in the pack extend at right angles to the side edges of the pack, there is merely a corrugating action and practically no separating action during the crimping process and the separating action 70 that takes place only during the flattening process. With the present method as best illustrated diagrammatically in Figs. 2 and 3, the formation of a corrugation in the pack starts at one edge or side of the pack and gradually works across the pack to the other edge. 75

By forming the corrugation in this manner, there is set up ahead of the corrugation proper, a reverse 10 wave in the pack itself which wave is diagrammatically illustrated in Figs. 2 and 3. This wave action across 80 the pack during the corrugating or crimping process tends to separate the sheets from each other as the pack is being crimped and it has been found that the sheets are better 85 separated at the end of the crimping action than they have heretofore been at the end of the flattening action. The flattening action in the present process completes the breaking apart of the sheets where this has not already been accomplished, and also substantially flattens the packs out again so that 90 the individual sheets are in a satisfactory flattened condition when received from the flattened rolls.

The use of the rolls with spiral flutes 95 makes the crimping action a sort of a continuous rolling motion across the pack which forms the corrugations in the pack in a gradual and continuous manner, and at the same time, tends to form the reverse waves 100 100 or crimps 10 just immediately ahead of the flutes and these reverse waves or crimps spread out some distance over the uncrimped pack and tend to break the sheets apart before they are crimped or corrugated. 105

It will of course, be understood that the crimping and flattening rolls may be used in series, that is, two or more sets of rolls can be used and where this is done, a second set of crimping rolls is preferably reversed as to 110 direction and angle of the flutes so that the second set of corrugations would run at the

opposite angle on the sheet to the first set. The same result can of course be accomplished by merely passing the pack through the rolls a second time and turning the pack 5 around before passing.

It will thus be seen that by crimping or corrugating with the use of spirally fluted or grooved rollers, that the separating action is obtained during the crimping process and 10 that a much better separating action is obtained than where the corrugations are formed at right angles across the pack, that is, where the complete corrugations is rolled into the pack at one time.

15 Other modes of applying the principle of my invention may be employed instead of the one explained, change being made as regards the method herein disclosed, provided the step or steps stated by any of 20 the following claims or the equivalent of such stated step or steps be employed.

I therefore particularly point out and distinctly claim as my invention:—

1. The method of opening sheet and tin 25 plate packs by rolling corrugations into the pack, each corrugation being thus rolled gradually from one side toward the other transversely of the direction of movement of such pack through the rolls, and then

passing the corrugated pack through flat- 30 tening rolls.

2. The method of opening sheet and tin plate packs by forming corrugations at an acute angle to the side of the pack and forming each corrugation gradually and continuously from one side to the other of the pack and then passing such corrugated pack through flattening rolls. 35

3. The method of opening sheet and tin plate packs by forming corrugations at an acute angle to the side of the pack and forming each corrugation gradually and continuously from one side to the other of the pack and then passing the corrugated pack through flattening rolls arranged to span a 40 plurality of such corrugations. 45

4. The method of opening sheet and tin plate packs by forming corrugations at an acute angle to the side of the pack and forming each corrugation gradually and continuously from one side to the other of the pack and then passing the corrugated pack through flattening rolls arranged to span a 50 plurality of but not all of such corrugations. 55

Signed by me this 12th day of May, 1921.

WILLIAM NEWBY.
